CLAIM

The ornamental design for a catamaran, as shown and described.

DESCRIPTION

1.1 is a front elevation view, with the stern flaps shown in an open position, of a catamaran embodying my new design;

1.2 is a bottom plan view thereof;

1.3 is a left side elevation view thereof;

1.4 is a rear elevation view thereof;

1.5 is a top, rear, right side perspective view thereof;

1.6 is a top plan view thereof; and

1.7 is a top, front, left side perspective view thereof.

2.1 is a top plan view of a second embodiment, with stern flaps shown in a closed position, of my new design;

2.2 is a front elevation view thereof;

2.3 is a bottom plan view thereof;

2.4 is a rear elevation view thereof;

2.5 is a left side elevation view thereof;

2.6 is top, rear, right side perspective view thereof; and

2.7 is a top, front, left side perspective view thereof.
